CONTROLLING DEVICE FOR GAS TORCHES

Charles D. Lawhon, Stratford, Conn., assignor to
 Robertshaw-Fulton Controls Company, Bridgeport, Conn., a corporation of Delaware

Application December 2, 1947, Serial No. 789,303

8 Claims. (Cl. 158—27.4)

1

This invention relates to a controlling device for a gas torch, and more particularly to an improved control device for reducing gas consumption in a gas torch.

It is an object of this invention to provide an improved control device for gas torches whereby the gas flame of the torch is reduced to a small flame comparable to a pilot flame, but not extinguished, when the torch is not in use, thereby to save gas consumption when the torch is not in service.

Another object of this invention is to provide an improved control device for gas torches whereby a safety factor is introduced so as to minimize accidents when the torch is not being used.

Another object of this invention is to provide an improved control device for gas torches which is so constructed as to facilitate adjustment of the flame of the torch, both as to the high flame when the torch is in use and the low flame when the torch is out of use.

Another object of this invention is to provide an improved control device for gas torches which provides a convenient rest for the torch when not in service.

Another object of this invention is to provide an improved control device for gas torches which minimizes the leakage of gas therefrom.

Another object of this invention is to provide an improved control device for gas torches which is composed of relatively simple parts that are easy to fabricate and assemble, and that which is certain and efficient in operation.

Other objects will appear as the description of the invention proceeds.

The invention is capable of receiving a variety of mechanical expressions only one of which is illustrated on the accompanying drawing, and it is therefore to be expressly understood that the drawing is for purposes of illustration only, and is not to be construed as a definition of the limits of the invention, reference being had to the appended claims for that purpose.

Referring in detail to the accompanying drawing wherein the same reference characters are used to designate corresponding parts in both figures,

Fig. 1 is an elevation of an embodiment of the present invention; and

Fig. 2 is a section, reduced in length by breaking away, along the axis of the embodiment shown in Fig. 1.

Referring in detail to the accompanying drawing, the embodiment shown comprises a body member 10 which may be of any suitable size,

shape and construction. Attached to body member 10, as by a suitable number of screws 11, is a bracket 12 provided with a portion 13 extending in any suitable direction and shown as apertured at 14 to receive attaching screws, so that the same may be secured in position on any suitable support, such for example as a work bench.

At one end, said body portion has any suitable provision for securing a source of mixed gas for use in the torch, the construction illustrated including a pipe 15 to which may be attached the mixed-gas supply hose, said pipe 15 being tapped at 16 for reception in a threaded recess 17 in the body member. Leading from the recess 17 is a passage 18 that communicates with a chamber 19 through a valve port 20. In lateral communication with passage 18 is a passage 21 which is in communication through a valve port 22 with passage 23, passages 21 and 23 constituting a by-pass around port 20.

Extending into the body member 10 in alignment with the valve port 22 is a threaded aperture 24 in which is mounted a by-pass valve member 25 which terminates in a member 26 for cooperation with port 22. Externally said by-pass valve member 25 is provided with a suitable head 27, which may be knurled to facilitate operation thereof in adjusting the member 26 toward and away from its port 22, and in order to secure the by-pass valve member against accidental displacement a lock nut 28 may be mounted on the threaded shank of said valve member for engagement with the body member 10.

At the opposite end of said body member 10 from the supply pipe 15 said body member is provided with an internally threaded recess 30 which terminates in a right angularly extending shoulder 31. Mounted on said shoulder 31, preferably with the interposition of a suitable gasket 32, is an annular flange-like member 33 to which is hermetically sealed in any suitable way a flexible wall in the form of an expandable and collapsible corrugated tubular wall or bellows 34 which subdivides chamber 19 into a gas chamber with which port 20 and passage 23 communicate and a second chamber at the opposite side thereof. The opposite end of said bellows 34 is hermetically sealed to a poppet valve member 35 adapted to cooperate with port 20. Annular member 33 is locked in position on the shoulder 31 by a base nut 36 provided with an internally threaded recess 37 and a passage 38 leading from said recess to the aforesaid second chamber between the inner face of the base nut and the bellows 34. Threadedly received in said recess 37 is a tu-

bular member in the form of a stanchion 38 which is threaded at its opposite extremity 39, and on said threaded extremity 39 is mounted a head member 40 provided with a chamber 41 and an opening 42 leading therefrom to the recess 43 which receives the threaded extremity 39 of stanchion 38. Pivotedly mounted on said head member 40 at 44 is a lever 45 which extends through the chamber 41 to the exterior of the head member 40 as shown at 46 where it may be given any desired shape, as the hooked configuration shown at 47, which may be of bifurcated construction if desired, to constitute a support from which the torch may be suspended when not in use. Extending between the lever 45 and the poppet valve member 35 is a thrust rod 48 which is guided in said stanchion and engages the under face of the lever 45 at one extremity and has a suitably shaped end 49, here shown as pointed, for engagement with or in a recess in the rear face of the poppet valve member 35, said rod 48 extending loosely but slidably through the aperture 42 in the head member 40, the internal bore 50 of the stanchion 38 and the aperture 37 in the base nut 36.

Head member 40 is also provided with a threaded opening leading into the chamber 41 at right angles to the length of lever 45, and threadedly mounted in said opening is a screw stud 51 whose outer end is provided with a head 52, that may be knurled to facilitate manipulation thereof. To lock the threaded stud 51 against accidental displacement a lock nut 53 may be mounted on the exteriorly threaded shank of said stud 51 for cooperation with the outer face of the head member 40.

Communicating with the chamber 19 in the body member 10 is any suitable pipe 55 to which may be attached the hose leading to the gas torch. As the torch may be of any suitable construction and its construction constitutes no part of the present invention, it has been omitted from the drawing for sake of clarity.

Bellows 34 is preferably formed of resilient metal so that when it has been extended by rod 48 moving poppet valve member 35 to close its port 20 the tension thereby imposed on said bellows will be sufficient to withdraw the poppet member 35 from its port 20 when rod 48 releases its pressure on the poppet valve member 35. However, if preferred, the action of the bellows may be supplemented by a spring to effect the operation now to be described.

In operation the body member 10 is installed on any suitable support by means of its bracket 12, 13, the source of mixed gas for use in the soldering, welding or comparable work is connected through any appropriate piping, hose or the like with the pipe 15, and the torch is connected to the pipe 55. When the torch is not in service it is hung on the hooked extremity 47 of the lever 45, 46, in which position its weight applied to lever 45 moves the latter downwardly around its pivotal axis 44, forcing the rod 48 downwardly to extend the bellows 34 and engage poppet valve member 35 with its port 20. In this position the main flow of gas through the port 20 is discontinued, but gas can still flow to the torch through the by-pass 21, 23 to the gas chamber which is in communication through pipe 55 with the torch. The size of the flame at the torch when the torch is not in service can be exactly predetermined by adjusting the by-pass valve member 25 so as to advance or withdraw its seating portion 26 with respect to its port 22, after which the lock

nut 28 may be positioned to secure the valve member 25 against accidental displacement.

When the torch is to be put into service it is withdrawn from the hooked extremity 47 of the lever 45, 46, whereupon the inherent resiliency in the bellows 34, supplemented by a spring as before referred to if desired, is sufficient to move upwardly the valve member 35, the rod 48 and the lever 45, 46 which is in engagement therewith, whereby poppet valve member 35 is withdrawn from its port 20 so as to provide the desired flow of gas through the gas chamber and pipe 55 to the torch. The size of this flame can be nicely predetermined by adjusting the threaded stud 51 which provides a positive stop for the lever 45, 46 in its upward movement, after which the threaded stud may be locked in position by the lock nut 53.

It will therefore be perceived that by the present invention a control device for a gas torch has been provided whereby a continuous flame is maintained at the torch, thereby overcoming certain disadvantages and inconveniences inherent in the use of a pilot flame interiorly of the control device where the pilot burner is difficult of access. Thus the gas consumption during the periods when the torch is not in service may be cut down to a minimum, appropriate for maintaining the small flame at the torch, by adjusting the by-pass valve member 25 so as to predetermine the quantity of gas flow through the by-pass 21, 23. At the same time the magnitude of the high flame at the torch can be readily predetermined at any time by adjusting the threaded stud 51 to limit the extent to which the port 20 is opened by the poppet valve member 35 through cooperation of said threaded stud 51 with the lever 45, 46. The bellows 34 provides a flexible seal between the chamber 19 and the passages through which lever 45, 46 and rod 48 control the poppet valve member 35, thereby minimizing gas leakage. Said lever also constitutes a convenient support for the torch when not in use so as to minimize accidents that may arise from laying the torch down on a bench or other support, while at the same time the act of hanging the torch on the lever assures reduction of the gas flame at the end of the torch to a minimum so as to reduce the likelihood of accidents as well as conserve gas. Additionally, the construction facilitates adjustment of the high gas flame because, by lifting the torch from the lever 45, 46, the magnitude of the high flame can be observed and then, by replacing the torch on said lever, the flame may be increased or decreased as desired by manipulation of the threaded stud 51. The control device, as will be observed, is composed of a relatively few number of simple parts that are easy to fabricate and assemble, while the resulting combination assures the desired control of the flame when the torch is in and out of service without discontinuing the flame when the torch is out of service.

While the embodiment of the invention illustrated on the drawing has been described with considerable particularity, it is to be expressly understood that the invention is not limited thereto, as the same may receive a variety of mechanical expressions, as will now be apparent to those skilled in the art, while changes may be made in the details of construction, proportion, arrangement, etc., of parts, parts may be replaced by equivalent parts, etc., without departing from the spirit of this invention. Reference

is therefore to be had to the appended claims for a definition of said invention.

What is claimed is:

1. A control device for gas torches comprising a body member containing a chamber, a flexible wall hermetically sealed in said chamber and subdividing the same into a gas chamber and a second chamber, means providing an inlet passage in communication with said gas chamber through a port, a valve member carried by said flexible wall and disposed in said gas chamber for cooperation with said port, a by-pass around said port communicating at its opposite ends with said inlet passage and said gas chamber, means providing an outlet passage in communication with said gas chamber, a thrust rod cooperating with said valve member in said second chamber, means carried by said body member for guiding said thrust rod, and a lever pivotally mounted on said last named means and cooperating with the end of said thrust rod, said lever providing a support on which the torch may be suspended and being movable under the weight of the torch to actuate said thrust rod and close said valve member.

2. A control device for gas torches comprising a body member containing a chamber, a flexible wall hermetically sealed in said chamber and subdividing the same into a gas chamber and a second chamber, means providing an inlet passage in communication with said gas chamber through a port, a valve member carried by said flexible wall and disposed in said gas chamber for cooperation with said port, a by-pass around said port communicating at its opposite ends with said inlet passage and said gas chamber, valve means for controlling said by-pass, means providing an outlet passage in communication with said gas chamber, a thrust rod cooperating with said valve member in said second chamber, means carried by said body member for guiding said thrust rod, and a lever pivotally mounted on said last named means and cooperating with the end of said thrust rod, said lever providing a support on which the torch may be suspended and being movable under the weight of the torch to actuate said thrust rod and close said valve member.

3. A control device for gas torches comprising a body member containing a chamber, a flexible wall hermetically sealed in said chamber and subdividing the same into a gas chamber and a second chamber, means providing an inlet passage in communication with said gas chamber through a port, a valve member carried by said flexible wall and disposed in said gas chamber for cooperation with said port, a by-pass around said port communicating at its opposite ends with said inlet passage and said gas chamber, means providing an outlet passage in communication with said gas chamber, a thrust rod cooperating with said valve member in said second chamber, means carried by said body member for guiding said thrust rod, a lever pivotally mounted on said last named means and cooperating with the end of said thrust rod, said lever providing a support on which the torch may be suspended and being movable under the weight of the torch to actuate said thrust rod and close said valve member, and means for adjusting the flame at the torch comprising an adjustable member cooperating with said lever to predetermine the extent to which said lever, and therefore said thrust rod and valve member, may move in an opening direction.

4. A control device for gas torches comprising a body member containing a chamber, a resilient

bellows hermetically sealed in said chamber and subdividing the same into a gas chamber and a second chamber, means providing an inlet passage in communication with said gas chamber through a port, a valve member carried by one end of said bellows and disposed in said gas chamber for cooperation with said port, a by-pass around said port communicating at its opposite ends with said inlet passage and said gas chamber, means providing an outlet passage in communication with said gas chamber, a thrust rod cooperating with said valve member in said second chamber, means carried by said body member for guiding said thrust rod, and a lever pivotally mounted on said last named means and cooperating with the end of said thrust rod, said lever providing a support on which the torch may be suspended and being movable under the weight of the torch against the resiliency of said bellows to actuate said thrust rod and close said valve member.

5. A control device for gas torches comprising a body member containing a chamber, a resilient bellows hermetically sealed in said chamber and subdividing the same into a gas chamber and a second chamber, means providing an inlet passage in communication with said gas chamber through a port, a valve member carried by one end of said bellows and disposed in said gas chamber for cooperation with said port, a by-pass around said port communicating at its opposite ends with said inlet passage and said gas chamber, means providing an outlet passage in communication with said gas chamber, a thrust rod cooperating with said valve member in said second chamber, means carried by said body member for guiding said thrust rod, a lever pivotally mounted on said last named means and cooperating with the end of said thrust rod, said lever providing a support on which the torch may be suspended and being movable under the weight of the torch against the resiliency of said bellows to actuate said thrust rod and close said valve member, and means cooperating with said lever to predetermine the extent to which said valve member may be opened by said resilient bellows upon removal of the weight of the torch from said lever.

6. A control device for gas torches comprising a body member containing a chamber, a flexible wall hermetically sealed in said chamber and subdividing the same into a gas chamber and a second chamber, means providing an inlet passage in communication with said gas chamber through a port, a valve member carried by said flexible wall and disposed in said gas chamber for cooperation with said port, a by-pass around said port communicating at its opposite ends with said inlet passage and said gas chamber, means providing an outlet passage in communication with said gas chamber, a thrust rod cooperating with said valve member in said second chamber, means carried by said body member for guiding said thrust rod, a head member carried by said last named means and provided with a chamber, and a lever on which the torch may be suspended pivotally mounted on said head member and extending through said last named chamber, said lever cooperating with the end of said thrust rod in said last named chamber to move said thrust rod under the weight of the torch when suspended on said lever to close said valve member.

7. A control device for gas torches comprising a body member containing a chamber, a flexible wall hermetically sealed in said chamber and subdividing the same into a gas chamber and a sec-

ond chamber, means providing an inlet passage in communication with said gas chamber through a port, a valve member carried by said flexible wall and disposed in said gas chamber for cooperation with said port, a by-pass around said port communicating at its opposite ends with said inlet passage and said gas chamber, means providing an outlet passage in communication with said gas chamber, a thrust rod cooperating with said valve member in said second chamber, means carried by said body member for guiding said thrust rod, a head member carried by said last named means and provided with a chamber, and a lever on which the torch may be suspended pivoted on said head member and extending through said last named chamber, said lever cooperating with the end of said thrust rod in said last named chamber to move said thrust rod under the weight of the torch when suspended on said lever to close said valve member, and said flexible wall having resiliency to open said valve member and move said thrust rod upwardly when the weight of the torch is removed from said lever.

8. A control device for gas torches comprising a body member containing a chamber, a flexible wall hermetically sealed in said chamber and subdividing the same into a gas chamber and a second chamber, means providing an inlet passage in communication with said gas chamber through a port, a valve member carried by said flexible wall and disposed in said gas chamber for cooperation with said port, a by-pass around said port communicating at its opposite ends with said inlet passage and said gas chamber, means providing an outlet passage in communication with said gas chamber, a thrust rod cooperating

5 with said valve member in said second chamber, means carried by said body member for guiding said thrust rod, a head member carried by said last named means and provided with a chamber, a lever on which the torch may be suspended pivoted on said head member and extending through said last named chamber, said lever cooperating with the end of said thrust rod in said last named chamber to move said thrust rod under the weight of the torch when suspended on said lever to close said valve member, and said flexible wall having resiliency to open said valve member and move said thrust rod upwardly when the weight of the torch is removed from said lever, and means carried by said head and cooperating with said lever for predetermining the extent to which said valve member may be opened by the resiliency of said flexible wall.
